Primary Examiner — Kevin K Rudzinski*Assistant Examiner* — Richard E Yenchesky(74) *Attorney, Agent, or Firm* — Jeenam Park(57) **CLAIM**

The ornamental design for a cleaning apparatus, as shown and described.

DESCRIPTION

FIG. 1 is a perspective view of a cleaning apparatus, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion of FIG. 1 thereof; and,

FIG. 10 is a perspective view with the lid open thereof.

The broken lines shown in the drawings illustrate portions of the cleaning apparatus that form no part of the claimed design.

1 Claim, 10 Drawing Sheets(56)
